(57) **CLAIM**

The ornamental design for a fuel tank, as shown and described.

DESCRIPTION

FIG. 1 is a perspective view of a fuel tank embodying my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken line showing of the cap is provided for the purpose of illustrating portions of the fuel tank that form no part of the claimed design.
